United States Patent Office.

WILLIAM WRIGHT, OF NEW YORK, N. Y.

Letters Patent No. 76,027, dated March 24, 1868.

IMPROVEMENT IN CUT-OFF VALVE-GEAR.

The Schedule referred to in these Letters Patent and making part of the same.

TO ALL WHOM IT MAY CONCERN:

Be it known that I, WILLIAM WRIGHT, of the city, county, and State of New York, have invented a new and useful Improvement in Operating the Cut-Off to Valves of Steam-Engines, of which the following is a full, clear, and exact description, reference being had to the accompanying drawing, forming part of this specification, and in which—

Figure 1 represents a rear view of the main valves as applied to a steam-engine cylinder, with my improved mode of giving a cut-off action to the same, and

Figure 2 a partly sectional view, taken mainly as indicated by the line $z z$ in fig. 1.

Similar letters of reference indicate corresponding parts.

My invention consists in a novel combination or arrangement of devices for operating the induction-valves of a steam-engine, and of giving to them a variable cut-off action, irrespective of the direction in which the engine travels, by combining with separate induction-valves, through suitable toes, two independently hung cams or wipers, the one of which serves to give a fixed or invariable opening-action to said valves on opposite sides of it, while the other operates to give a variable closing or cut-off action to such valves, the opening and closing or cut-off toes for the one valve being disconnected from the opening and closing toes of the other valve, and each of these independent sets of toes, on opposite sides of the cams, being geared together, so that the separate induction-valves have both their opening and closing or cut-off action given them from the same side of the cams, operating shaft or shafts on or next to which they lie.

Referring to the accompanying drawing, A represents the cylinder of an ordinary reciprocating piston-engine, and B B' valve-boxes or chambers at opposite ends thereof, the same being supplied with steam in the usual or any suitable manner, and being provided with independent valves C C', preferably of a gridiron character, though other forms may be used, and operating, as they are reciprocated or thrown, to establish alternately at opposite ends, communication of the engine-cylinder with the steam-spaces of the valve-boxes.

These separate or independent valves have connected with them in an adjustable manner, or otherwise attached to the outer ends of their stems a a', sliding toes D D', that are alternately operated by a revolving wiper, E, in either direction of the engine's travel, to open the valves for the admission of steam to the engine-cylinder in a constant and regular manner, without regard to the cut-off action of said valves, the wiper E being, say, a projection from or attachment to a sleeve or hollow shaft, F, which derives its motion by bevel-gearing, b c, from the main shaft of the engine in any desired manner. In this way is a sudden or quick and fixed or invariable opening-action given to the valves C C', in whichever direction the engine runs, by reason of the double- or similar reverse construction of the sliding toes D D' and wiper E, to alternately open said valves for the admission of steam to the engine-cylinder.

To establish the cut-off action in a mechanical or positive manner to these separate or independent valves, without or instead of merely depending upon gravity, or the aid of springs to effect their closing, and this in a variable manner, which may be under the control of the governor, or hand, as desired, I cause a separate revolving wiper, G, to act upon independent sliding toes H H', both constructed to similarly operate under either or both directions of the engine's travel, and so couple or hang said wiper, and connect said sliding toes with the valve-stems or toes immediately connected therewith, so that accordingly as the toes H H' are operated sooner or later, they serve to give the cut-off action to the valves that is, shut off further ingress of steam through them to the engine-cylinder. To secure the necessary revolving motion to the wiper G, in common with the wiper E, and adjustability or lead or throw of the former to establish a variable cut-off under control of the governor, the independent wiper G is here shown as driven or revolved by a shaft, I, in feather-gear with the hollow shaft F, so as to rotate with and be driven by the latter, but free to move longitudinally through it, and said inner shaft I, geared with the independent wiper G, by means of a spiral thread or groove, d, so that while the revolving of the shaft F, with its wiper E, induces a like motion to the independent wiper G, the latter is adjusted or set, by its spiral gear, with the shaft I, to give an earlier or later cut-off action to the valves by the sliding action longitudinally of the inner shaft I, accordingly as, say, the governor so controls or actuates the shaft I. The independent sliding toes H H', on or against which the wiper G acts, are here shown as geared with the valve-stems or primary toes D D' by means of levers, J J', working on intermediate pivots or centres

e e', but other connections may, of course, be substituted, as may other arrangements or dispositions of parts be adopted for establishing simultaneous rotation of the wipers *E* and *G*, with independent adjustability, while rotating, of the latter wiper under control of the governor to establish a variable cut-off, as described. Thus the shaft *I* might have a fixed relationship, so far as any longitudinal action is concerned, and be carrying or driving one of the primary wipers, *E*, while the cut-off wiper, *G*, might be in spiral gear with said shaft, and have a longitudinal motion under control of the governor, with suitable depth or length of operating-surface to insure its action on the toes *H H'*, under any or every adjustment of it, or the primary wiper, *E*, might be connected so as to have a straight, longitudinal, as well as rotary motion, or the spiral connection of the cut-off wiper, *G*, with an operating-shaft or sleeve be established on the outside of it.

By this mode of operating the separate induction-valves of an engine, not only is a fixed or invariable and sudden and full action communicated to said valves, so far as their opening is concerned to admit steam to the engine-cylinder, and a variable cut-off motion, under control of the governor, given to said valves in a mechanical or positive manner, so as to cut off as early or late as desired in the piston's stroke, but said separate induction-valves have the four motions, that is, two to each valve, namely, opening and closing, given them by but two cams or wipers, and by the arrangement of the levers *J J'*, coupling, respectively, the sliding toes *D H* and *D' H'*, both the opening and closing actions are given to said valves on or from the same side of the shafts *I* and *F* as that on which either valve lies, thus dispensing with yokes for operation from opposite sides of the cam's shaft or shafts, also with extra cams or wipers for thus operating separate induction-valves, each of which, it will be seen, by this combination of devices, is separately controllable through the one cam, as regards cut-off, by reason of the disconnected relationship of the toes *H H'*. The necessary induction-valves are not here shown, as they form no part of this invention.

What is here claimed, and desired to be secured by Letters Patent, is—

The combination, with the separate induction-valves to opposite ends of the engine-cylinder, of the fixed cam *E* and variable cam *G*, arranged for action in either direction of the engine's travel, substantially as described, opening and cut-off toes *D H* and *D' H'*, geared by levers *J J'*, or their equivalents, for joint but independent action in opposite sides of the axes of the cams, and whereby not only are the valves opened and closed independently of each other, and each made capable of different cut-off strokes by the action of said cams on the toes, but whereby both the opening and closing movement is given to either valve, respectively, from the same side of the axes of the cams as that on which the valve lies, essentially as herein set forth.

WM. WRIGHT.
